REAR VIEW MIRROR

Robert R. Rossi, Audubon, N. J., assignor to Peerless Accessories Co., Mount Holly, N. J., a corporation of New Jersey

Application November 6, 1956, Serial No. 43,679

Term of patent 14 years

(Cl. D14—6)

FIG. 4.

FIG. 3.

FIG. 1.

FIG. 2.

I claim:

The ornamental design of a rear view mirror, as shown.
